UNITED STATES PATENT OFFICE.

PATRICK KELLY, OF NASHVILLE, TENNESSEE.

IMPROVEMENT IN SPARK-ARRESTERS.

Specification forming part of Letters Patent No. **69,817**, dated October 15, 1867.

To all whom it may concern:

Be it known that I, PATRICK KELLY, of Nashville, in the county of Davidson and State of Tennessee, have invented a new and useful Improvement in Locomotive Smoke-Stacks; and I do hereby declare that the following is a full, clear, and exact description thereof, which will enable those skilled in the art to make and use the same, reference being had to the accompanying drawings, forming part of this specification.

This invention relates to a new and improved method of forming the smoke-stacks of locomotives, whereby the sparks are arrested and conducted to the ground; and the invention consists in placing within the chimney certain arresters, deflectors, and conductors, which not only prevent the escape of the sparks from the chimney, but collect and discharge them, as will be hereinafter more fully described.

Figure 1 is a sectional elevation of the smoke-stack with its interior arranged according to my invention. Fig. 2 is a cross-section through the line *xx* of Fig. 1.

Similar letters of reference indicate corresponding parts.

A represents the boiler. B is the base or saddle of the smoke-stack. C is the drum or body of the smoke-stack. D is the smoke-flue. E is a truncated cone surrounding the top of the flue D. E' is an annular space around the flue D. F is the spark arrester and deflector, which is placed directly over the flue and cone D E. F is supported in its place by rods *aa*, which are attached to the flue D. G is the cap, forming a conical-shaped chamber, in the

usual manner, in which the spark-arresting device is placed. This cap is surmounted by a band, H, which is attached to it, within which is an adjustable ring, *c*, which extends down below the top of the cap when desired, so that the draft of the chimney can be regulated and the sparks arrested thereby. J is a conductor or chute, which is attached to and surrounds the flue D, placed diagonally on the flue, as represented in the drawing. The lower ends do not join, but are so shaped that they form a spout for the discharge of the sparks into the tube K, from whence they drop onto the ground, being conveyed through the smoke-box and near to the ground by the tube. The sparks, after passing up through the flue D, are arrested by F, and drop from thence onto the cone E, from whence they slide onto the bottom of the cap G. From thence they drop onto the conductor or chute J, which conveys them to the tube K, which discharges them through the smoke-box to the ground, as before mentioned.

The tube K can be detached for the purpose of removing the trucks from under the locomotive when desired.

What I claim, and desire to secure by Letters Patent, is—

The combination of the spark-arrester F, cone E, flue D, drum C, cap G, conductor J, tube K, band H, and adjustable ring *c*, as herein set forth, for the purpose specified.

PATRICK KELLY.
